UNITED STATES PATENT OFFICE.

HENRY JAMES MAGRATH, OF POPLAR, LONDON, ENGLAND.

TREATMENT OF WATER FOR SOFTENING, PURIFYING, AND LIKE PURPOSES.

1,239,202.

Specification of Letters Patent.

Patented Sept. 4, 1917.

Application filed November 22, 1916. Serial No. 132,819.

To all whom it may concern:

Be it known that I, HENRY JAMES MAGRATH, a subject of the King of Great Britain, and residing at 196 High street, Poplar, London, England, have invented certain new and useful Improvements Relating to the Treatment of Water for Softening, Purifying, and like Purposes, of which the following is a specification.

10 This invention relates to systems of softening, purifying, and otherwise treating water, in which systems a base-exchanging material such as natural or artificial zeolites is used requiring to be regenerated at intervals. It is the object of the invention to provide a simple and inexpensive form of the apparatus such as can be used for supplying softened or treated water to a lavatory basin or the like whenever required. 15 20 The invention also includes an improved method of operation associated with the new apparatus. The types of apparatus hitherto known have generally been adapted to receive the water to be treated at full pressure from the mains, and it becomes an expensive matter to make a cylinder to contain the filtering material, the zeolite and the like, which cylinder will stand the main pressure continuously, while having the various taps or cocks necessary for controlling the flow and for use during regenerating. Again, such apparatus even if made as small as possible for supplying a single basin or the like, is still somewhat bulky while its 25 30 35 cost of manufacture is rather high.

These difficulties are overcome by the simplified or improved type of apparatus and the modified method of operation during regenerating, forming the subject of the present invention.

In the accompanying drawings:—

Figure 1 is a front elevation showing a suitable form of the apparatus.

Fig. 2 shows a vertical section of the tank. 45 Fig. 3 shows a plan view of the tank, and Figs. 4 and 5 are detail views of the three-way cock, Fig. 4 being an elevation and Fig. 5 a horizontal section on the line A—B of Fig. 4.

50 In the drawings *a* represents a wooden board or base suitably secured to a wall and having the tank *b* mounted thereon for instance by lugs *c*. The front of the tank may be provided with a frame carrying a looking glass *d*, Fig. 1, while at the sides hooks may be provided as indicated at *e*,

Fig. 1, for hanging up brushes and so forth. These hooks are not indicated in the other figures.

In the bottom of the tank is provided a 60 socket member *f* having a tube *g* brazed therein, the socket member being bolted through the bottom of the tank to a member *f'* into which screws the stem *h* of the cock *s*. The flange of the socket member *f* may be 65 packed in any convenient way, and for example a rubber disk *k* is shown between the member *f'* and the underside of the tank. The pipe *g* which is open to the stem *h* in the socket member *f*, is closed at its end *l* 70 and has a number of holes or saw-cuts formed in its bottom portion at each side of the socket member *f* so as to permit water to flow into the said pipe and to reach the cock *s*. The pipe *g* preferably extends upwardly to the top of the tank as seen in Figs. 2 and 3, where it may be closed by a plug *m* of hard material such as ebonite. This only requires to be removed on special occasions as hereinafter explained. *n* is an 80 overflow pipe extending upward to near the top of the tank leading to an overflow outlet. In the example shown it extends downwardly to a socket *o* at the bottom of the tank from which any overflow water may 85 flow out to waste. In the upper part of the tank a ball valve *p* is fitted, operated by means of a ball float *q* of usual type, the valve being one which is capable of working at the normal pressure of supply for 90 domestic purposes. At the bottom of the tank is a layer of filtering material such as gravel *r* which lies over the perforated pipe *g* and extends up for an inch or two from the bottom. Above this is a layer *t* of softening or purifying material, which for convenience may be referred to generally here as base-exchanging material, and of which the well-known permuit forms a good example. This extends up nearly to the level 100 of the ball valve, while the valve maintains the water level a little above the top of the base-exchanging material. There is enough space in the tank above the normal water level to admit of the pouring in of a solution containing the requisite amount of salt for regenerating purposes, without filling up quite to the level of the top of the overflow pipe *n*. In the example shown the tank may be supposed to be about 27 inches 105 in height from top to bottom, 4 inches in depth from back to front and 12 inches in 110

width internally. If this is so then in the example shown the gravel layer is about 2 inches in height, the permuit layer about 14 inches in height, the water level above the 5 permuit about 3 inches higher, and there is still a height of about 6 inches above that level up to the overflow. These dimensions are mentioned purely by way of example.

The cock *s* illustrated turns around the 10 stem *h*, and has a pipe *u* extending outward from it, formed for example as shown in Fig. 2 to receive a rubber hose or other connection to carry away the water to another point when required. The stem *h* 15 is conical and has two apertures therein, the larger one at *v* being for the normal outflow of purified water, while the smaller one at *w* is meant for use in regenerating only. The cock is shown in the closed position in 20 Figs. 4 and 5. When turned around the stem *h* through 90° to the forwardly extending position as in Figs. 2 and 3, the main port *v* is opened. When turned through a further 90° the port *w* is opened 25 to allow a slow trickling flow of liquid therethrough. The port *w* may for instance be a small hole about one-thirtysixsecond of an inch in effective diameter.

During normal working water will only 30 be drawn off occasionally, and usually no large amount will be drawn off at a time, so that what is drawn off will have been standing in the tank in contact with the material *t*, and it will have been purified, softened 35 or otherwise treated thereby. As any water is drawn off from the cock *s*, more flows in through the ball valve *p* and slowly percolates downward through the material *t* and the gravel layer *r*. Such an apparatus will 40 only require regenerating at comparatively long intervals of time, and when it is required, either salt can be thrown into the tank in the water above the top of the material *t*, or preferably the required amount 45 of salt can be dissolved in water and poured in as already mentioned. For the amount of material such as permuit contained in a tank of the dimensions mentioned above, about 3 lbs. of salt would probably suffice 50 for regenerating, and this would not require more water for dissolving than would easily be contained in the six inches free height in the tank above the normal water level up to the top of the overflow pipe *n*. The 55 swiveling member of the cock *s* should now be turned to the left hand position allowing a slow trickling flow of liquid therefrom, and the apparatus should be left with the cock in this position preferably over night, 60 and at any rate for a period of about eight to ten hours. The salt solution becomes diffused through the water already in the tank and slowly percolates through the material *t*, any waste solution being allowed to 65 flow out through the cock *s*, while when the

water level has fallen below the normal, fresh water is slowly admitted through the valve *p*, and in the period mentioned sufficient water will have been admitted after all the spent salt solution has flowed out, 70 to wash the filtering material free from any remainder of salt. The tank will be full of fresh water, and this will be ready for use. The cock must be turned of course to the normal closed position shown in Figs. 4 and 75 5 until water is required.

It will be seen that there is only one cock or tap to be operated for the whole system, and that no special instructions are required for regenerating on the above-described plan. It is, however, possible to effect the regeneration in a somewhat different way; for example if a cock is provided in the pipe leading to the ball valve *p*, the main water supply can be cut off altogether and the water can be drained from the tank with the cock member *s* in the position of Figs. 1 and 2. The cock can then be closed as in Figs. 4 and 5, and the tank filled up with salt solution. A more dilute solution must be prepared in this case in order to fill up the tank to the required level. If this is done it is important to avoid imprisoning air in the active material, and hence the filling should be effected 95 through the pipe *g*, the plug *m* being removed for this purpose. The salt solution then enters through the holes in pipe *g* at the bottom of the tank, so that it enters from the bottom displacing any air upwardly. The salt solution can be allowed to run out slowly with the cock *s* in the left hand position while fresh water for washing purposes is either poured in above the active material, or is allowed to flow in 100 from the main through valve *p*. This latter method of operation requires more attention and is in some ways not so reliable as the first described method according to which the regeneration always takes place 110 automatically with subsequent washing under identical conditions. Hence the first described method of working is preferred.

The tank need not necessarily be flat, though this form is preferred. It must be 115 of sufficient width at any rate at the top to accommodate a ball valve *p*, *q* which will be large enough to operate effectively under the pressure conditions in the supply pipes. The tank may be of porcelain or enameled 120 iron, and all internal fittings should preferably be tinned, so that they will not be attacked by the salt solution. If the tank is never emptied there is very little risk of rusting of internal fittings. The invention 125 is not limited to the use of any particular active material and zeolites have been mentioned by way of example only. Any equivalent base-exchanging material suitable for softening, purifying and for like 130

purposes may be used. The material used may include constituents adapted to remove hardness, traces of iron or any other undesired constituents from water as supplied, 5 and the constitution of the salt used for regenerating will depend as is well understood on the character of the active material employed.

Having thus described my invention what 10 I claim as new and desire to secure by Letters Patent is:—

1. Apparatus for softening, purifying and otherwise treating water, consisting of a tank, a base-exchanging material in said 15 tank, a ball valve so disposed as normally to maintain a depth of water in the tank above the base-exchanging material, and a single outflow cock having two separate outlet ports, one large and the other comparatively 20 small, said cock being adapted in one position to close both ports, in a second position to be turned to open the large outlet port for the normal flow of treated water, and in a third position beyond the second to open 25 the small outlet port in order to allow of a slow trickling flow at a predetermined rate during regeneration of the base-exchanging material.

2. Apparatus for softening, purifying and otherwise treating water, consisting of a tank, a base-exchanging material in said 30 tank, a ball valve so disposed as normally to maintain a depth of water in the tank above the base-exchanging material, an over- 35 flow pipe in said tank having its overflow opening at a level so far above the normal water lever maintained by the ball valve, as to accommodate in said tank between said normal level and the overflow level the re- 40 quisite amount of solution for the regeneration of the base-exchanging material, and a single overflow cock having two separate outlet ports, one large and the other comparatively 45 small, said cock being adapted in one position to close both ports, in a sec- 90 ond position to open the large outlet port for the normal flow of treated water, and in a third position beyond the second to open the small outlet port in order to allow of a slow trickling flow at a predetermined rate dur- 95 ing regeneration of the base-exchanging material.

to allow of a slow trickling flow at a prede- 50 termined rate during regeneration of the base-exchanging material.

3. Apparatus for softening, purifying and otherwise treating water, consisting of a tank, a base-exchanging material in said 55 tank, a ball valve so disposed as normally to maintain a depth of water in the tank above the base-exchanging material, a perforated pipe within said tank near the bottom there- 60 of, a socket member communicating with said perforated pipe and a single outflow cock also communicating with said perforated pipe, said outflow cock having two separate outlet ports, one large and the other comparatively small, said cock being adapt- 65 ed in one position to close both ports, in a second position to open the large outlet port for the normal flow of treated water, and in a third position beyond the second to open the small outlet port in order to allow 70 of a slow trickling flow during regeneration of the base-exchanging material.

4. Apparatus for softening, purifying and otherwise treating water, consisting of a tank, a base-exchanging material in said 75 tank, a ball valve so disposed as normally to maintain a depth of water in the tank above the base-exchanging material, a perforated pipe within said tank near the bottom there- 80 of and with an extension leading up to the top of the tank adapted to receive regenerat- 85 ing solution poured therein and to carry the same to the perforations in the lower end of the pipe, a socket member communicating with said perforated pipe and a single out- 90 flow cock also communicating with said perforated pipe, said outflow cock having two separate ports, one large and the other com- 95 paratively small, said cock being adapted in one position to close both ports, in a sec- ond position to open the large outlet port for the normal flow of treated water, and in a third position beyond the second to open the small outlet port in order to allow of a slow trickling flow at a predetermined rate dur- 95 ing regeneration of the base-exchanging material.

HENRY JAMES MAGRATH.
